UNITED STATES PATENT OFFICE

ARTHUR BINGHAM, OF LONDON, ENGLAND

SHEET REGISTERING DEVICE FOR USE IN PRINTING AND THE LIKE MACHINERY

Application filed July 22, 1930, Serial No. 472,688, and in Great Britain August 2, 1929.

This invention relates to improvements in sheet registering devices for use in printing and like machinery, and had for its object the provision of means for ensuring that a sheet is correctly registered when it is transferred from one unit of a machine to another. For instance, in a multi-colour printing machine it is essential that the sheet shall be correctly registered in each printing unit in order that the various colour impressions shall be correctly disposed with respect to one another.

The present invention comprises a sheet registering device wherein stops are arranged on or near the periphery of the printing or like rollers, adapted to receive the leading edge of an incoming sheet and correctly register the same, and means are provided for removing the stops from the path of the sheet as the latter commences to pass between the rollers.

The invention will be more particularly described with reference to the accompanying drawings, in which:—

Fig. 1 is a diagram of a small portion of a printing machine showing the invention applied thereto.

Fig. 2 is an enlarged view of the impression roller of the machine.

Fig. 3 is a sectional elevation of Fig. 2.

Fig. 4 is a diagram of a modification of the invention.

Referring to Fig. 1, a web of paper 1 is fed in the direction of the arrow to a pair of cutting rollers 2 which sever the web into sheets of the required length. An intermediate pair of feed rollers 3 pass the cut sheet to the printing mechanism comprising an engraved roller 4 rotating in a bath of ink 5 and furnished with a scraper or doctor 6 in the usual manner.

The impression roller 7 is provided with an automatic stop or registering device 8 which will be described in more detail with reference to Figs. 2 and 3.

Referring to Fig. 2, it will be seen that the impression roller 7 is hollow and has a recess 9 cut in one portion of its periphery, the recess being about equal in depth to the thickness of a sheet of paper. A hole 10 is cut in the wall of the hollow drum at the recessed portion, and the stop 8 projects through the hole, the extremity of the stop being coincident with the periphery of the roller. The stop is loosely pivoted on the shaft 11 of the impression roller and a pin 12 in the boss of the stop works in a slot 13 formed in a cam lever 14. The cam lever 14 is pinned to a shaft 15 journaled in the roller, and the outer end of the shaft 15 is fixed to an arm 16 carrying a cam roller 17 which runs on a cam 18 adjustably fixed to the frame of the machine.

When a sheet is fed into the printing unit from the cutting unit the stop 8 is in the vertical position shown in Fig. 2 and forms an abutment which exactly registers the front edge of the sheet. The stop 8 remains fixed for a short time as the motion of the cam roller up the incline 19 of the cam neutralizes the motion of the stop 8 due to the rotation of the roller 7 so that the stop remains stationary until the roller reaches the top of the cam at which instant the end 20 of the hole 10 also reaches the stop, after which the stop rotates with the roller.

As the stop 8 and surface 20 contact, the working surface of the roller 7 also contacts with the sheet and carries it forward in conjunction with the printing roller 4.

It will be seen that if the apparatus is so adjusted that the roller 17 reaches the top of the cam before the stop 8 contacts with the surface 20, there would be a tendency for the roller 17 to rise owing to its momentum, and in order to prevent this, the arm 16 is provided with another roller 21 which runs on the lower surface of the cam and prevents any such displacement of the stop 8 owing to the momentum of the parts.

A pair of springs 22 are attached to the stop 8 to take up any play in the moving parts.

Referring to Fig. 4, it will be seen that the impression roller 22^a is carried on an arm 23 pivoted at 24 to a fixed portion of the machine and a roller 25 mounted on an extension 26 of the arm 23 runs in contact with a cam 27 mounted on the printing roller 28 so that the roller 22^a is lifted out of contact with the roller 28 for a small portion of a revolution during which time the registering of the sheet takes place.

A spring 29 pulls the roller 22^a into contact with the roller 28 when the cam 27 permits this movement. In this case the stop is in the form of a shroud 30 loosely pivoted on the spindle 31 of the roller 22^a and an arm 32 furnished with a roller is operated by a cam 33 to remove the shroud 30 from the position shown in the figure. As the roller 22^a commences to drop on to the roller 28 the cam 33 which is driven by gears, as shown, commences to lift the shroud and after the sheet has registered against the vertical edge of the shroud the same is swung out of the path of the sheet as the roller 22^a drops.

Although I have described the invention as applied to printing machines, it will be obvious that it can be applied to other forms of machinery where it is desired to feed a sheet from one unit to another and maintain accurate register of the same.

What I claim as my invention and desire to secure by Letters Patent is:—

1. A sheet registering device adapted to be employed in connection with impression cylinders of printing presses or the like, comprising, in combination, a stop disposed adjacent the periphery of said cylinder and comprising a pivoted member carried by said cylinder and adapted to receive the leading edge of an incoming sheet and correctly register the same, and a cam adapted to actuate said stop to cause it to remain stationary during the registration of the sheet and to move together with said impression cylinder when registration is effected.

2. In combination with an impression cylinder of a printing press or the like which is mounted upon a shaft and is adapted to rise and fall with relation to a printing roller, a sheet registering device comprising, in combination, a stop pivoted to the shaft of said cylinder and means including a cam for causing said stop to remain stationary during the registration of the sheet and to move out of the path of the sheet as the impression cylinder moves toward the printing roller.

3. In combination with a hollow printing or like cylinder which is provided with a spindle, a sheet registering device consisting of a stop pivoted upon said spindle and adapted to extend through and beyond the periphery of said cylinder, means for oper-

ating said stop periodically to receive the leading edge of an incoming sheet and arresting the same so as to register correctly each sheet relatively to the cylinder, said operating means comprising a cam or the like and adapted to cause said stop to remain stationary during the registration of a sheet and to cause it to move together with the cylinder when registration is effected.

In testimony whereof I hereunto affix my signature.

ARTHUR BINGHAM.
